COMBINED RAZOR BLADE AND MOUNT

Bernard S. Hansom, Langley, England, assignor to
Wilkinson Sword Limited, London, England, a
British company

Filed Oct. 22, 1968, Ser. No. 14,109

Term of patent 14 years

Claims priority, application Great Britain, Apr. 24, 1968

Int. Cl. D28—03

U.S. Cl. D95—3

FIG. 1. FIG. 2.

FIG. 3.

FIG. 4.

FIG. 5.

FIG.6. FIG.7. FIG.8. FIG.9. FIG.10. FIGURE 1 is a side elevational view of a combined razor blade and mount showing my new design;

FIGURE 2 is a front elevational view thereof;

FIGURE 3 is a plan view of the design of FIG. 1 wherein three slots are provided in the top;

FIGURE 4 is a rear elevational view thereof;

FIGURE 5 is a plan view thereof wherein the bottom has several openings;

FIGURE 6 is a side elevational view of a modification of the design of FIG. 1;

FIGURE 7 is a front elevational view of the design shown in FIGURE 6;

FIGURE 8 is a rear elevational view of the design shown in FIGURE 6;

FIGURE 9 is a plan view of the design of FIG. 6 wherein a single slot is provided in the top; and

FIGURE 10 is a plan view of the design of FIG. 6 wherein the bottom is plain.

I claim:

The ornamental design for a combined razor blade and mount, as shown and described.
